Primary Examiner — Kendra Leslie Hamilton*Assistant Examiner* — Amanda Christensen*(74) Attorney, Agent, or Firm* — Lee & Hayes, P.C.(57) **CLAIM**

The ornamental design for a charging clip, as shown and described.

DESCRIPTION

FIG. 1 is a top, front, right-side perspective view of a charging clip, showing our new design;

FIG. 2 is a top, back, left-side perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The dashed broken lines depict portions of the charging clip that form no part of the claimed design.

1 Claim, 8 Drawing Sheets(56)
